UNITED STATES PATENT OFFICE.

HENRY FERGUSON, OF LONDON, ENGLAND.

APPARATUS FOR EVAPORATING AND CONDENSING WATER.

SPECIFICATION forming part of Letters Patent No. 439,132, dated October 28, 1890.

Application filed December 3, 1889. Serial No. 332,404. (No model.)

To all whom it may concern:

Be it known that I, HENRY FERGUSON, of London, England, a subject of the Queen of Great Britain and Ireland, have invented an Improved Evaporating and Condensing Apparatus for Producing Fresh Water from Sea-Water for Drinking Purposes and for Boiler-Feed, of which the following is a specification.

My invention relates to an improved apparatus for the evaporation and condensation of fresh water from sea-water or other liquid for drinking purposes or for boiler-feed, and is designed to effect the same by means of especially simple and convenient apparatus and in an economical manner.

By a well-known law water under a vacuum enables the evaporation to be effected at a comparatively low temperature, and this law I take advantage of in carrying out the evaporation of sea-water under a vacuum by means of steam, utilizing the preheated condensing water for evaporation. The vacuum under which the steam is evaporated is produced by first expelling the air from the evaporator and condenser by allowing the steam to blow through them or by the exhaustive action of the condensed-water pump, and then upon allowing the cooling water to circulate in the condenser the steam coming from the evaporator is condensed and a partial vacuum is consequently produced, the water resulting from such condensation being withdrawn from the condenser continuously by the condensed-water pump.

As all marine boilers from which the steam is condensed in surface-condensers after use lose some portion of the said steam by leakage or other causes while in operation, it is most important to supply this constant loss of feed-water from some fresh-water source, otherwise the objects for which such an expensive apparatus as a surface-condenser and its accessories are used would be defeated, as any addition of sea-water to make up for the loss of fresh water seriously deteriorates from the efficiency and safety of the boiler, particularly in the case of high-pressure or multi-tubular boilers used with forced draft, such as those employed in torpedo-boats. My apparatus, then, in addition to being suitable for the production of fresh water for the supply of that water lost by leaks from the boiler

and in other ways, is also particularly applicable for the production of a supply of filtered aerated drinking water.

55

I am aware that apparatuses have been known for some time past for the evaporation of salt-water and its condensation into fresh water; but the particular objects of my invention are to afford means whereby the use 6c of high-pressure steam for evaporating the sea-water in the evaporator can be employed by which a high duty may be obtained from an apparatus of small weight and occupying little space, particular regard being had to 65 special arrangements for the easy and rapid circulation of the salt-water in the evaporator, and also the production of saturated steam from the same, in order that the resulting water from the condensation of the steam may 70 be practically pure and fresh, for should the steam be saturated to any extent with the salt-water it would be carried over into the condenser, and the water, which should have been fresh, would have a brackish taste.

75

In order that my invention may be the better understood, I will now proceed to describe the same, reference being had to the drawings hereunto annexed, and to the letters marked thereon.

80

Like letters refer to like parts throughout the figures.

Figure 1 is a part sectional elevation of my apparatus. Fig. 2 is a part sectional plan of the same. Fig. 3 is a sectional plan of the 85 aerating and filter pump through the line X X, Fig. 1. Fig. 4 is a detail sectional view of my evaporator on the line X X. Fig. 5 is a plan view of the same. Fig. 6 is a section on the line Y Y. Fig. 7 is a section on the line Z Z. 90

In order to carry my invention into effect I preferably arrange the evaporator A within the center of the condenser B, which is an annular chamber, the intervening space between the two chambers being packed with a 95 non-conducting material, such as asbestos packing or other similar material. The evaporator A has a diaphragm a arranged at the top and another a' at the bottom, which form the tube-plates, and between these tube-plates 100 the tubes C are supported. Upon each side of the chamber d is a passage or passages E E, which form a connection between the upper and lower chambers of the evaporator, so

that the heated water as it rises up the tubes C can return by the passages E E, whereby a complete system of flow and return is set up. The steam for evaporating purposes is admitted through the pipe f and the hollow door F, entering the chamber d through the orifice f', surrounding the tubes C C and communicating its heat thereto. The condensed water resulting from such steam as it parts with its heat is withdrawn by the pipe g through the door G.

Upon the upper part of the evaporator A, I arrange a still-head H, having a neck at the lower end of such a size as will embrace the whole space covered by the tubes C C and passages E. The upper part of the still-head is of larger diameter, and has suspended from the top cover J a circular baffle-plate j, extending downward till it nearly reaches the neck. This baffle-plate has a vertical slot j' extending from the cover J to nearly the bottom of the plate, and on each side of the slot within the annular space around the outside of the baffle-plate another baffle-plate K K' is arranged, reaching from the cover J, near the top of the slot j', and lying in an angular position a certain distance round the annular space, the lower part of the plates K K' extending rather more than half-way down the baffle-plate j.

The exit-pipe L to the condenser is taken out of the still-head H at a point on the opposite side of the head as that on which the slot j is situated, and has its connection with the still-head so arranged that the greatest volume of steam is taken from the upper part of the still-head, so that it shall be as dry as possible.

The condenser B is, as hereinbefore described, an annular chamber placed around the evaporator A, and has the tube-plates b b' on the upper and lower ends of the chamber supporting the tubes c' of dome-section, which form the circulating-chambers above and below the tubes C. The steam is conveyed to the condenser from the evaporator by the pipe e entering the condenser at e', where it condenses between the tubes c, and is drawn through the pipe d' by the fresh-water pump D from the bottom of the condenser, where it collects. The circulating water is forced by the circulating-pump P through the tubes in the condenser, entering at h and leaving at h'. The brine which collects at the lower part of the evaporator is drawn away by the pump g' through the pipe g² to the delivery-pipe g³. The feed-water for the evaporator is regulated and kept at a constant height by a self-acting valve m, arranged within a chamber M. This valve is of the ordinary double-beat type, and has arranged a certain distance up the valve-spindle a float of any suitable material, such as copper. The feed-pipe R', which is led from the circulating delivery-pipe R so that the feed-water may be as hot as possible, enters the chamber M at the side, so that it is in communica-

tion with the regulating-valve m. A pipe l is led from the bottom of the chamber M to the bottom of the evaporator, and a similar pipe l' is led from the top of the chamber M to the pipe e, so that the bodies of water in the chamber M and the evaporator are in equilibrium, and it follows that if the feed-valve chamber is in a proper position relatively to the evaporator a constant level will be maintained in the latter by the automatic regulation of the supply by the valve m being governed by the level of the water in the chamber M.

In conjunction with this apparatus I use a steam-pump N of a very compact and ingenious construction in which the five pumps for various purposes—viz., circulating-pump P, fresh-water pump D, aerating-pump D', brine-pump g', and feed-pump for boiler g⁴—are driven direct from one steam-cylinder O² through the medium of a cross-head O, situated directly opposite to the steam-cylinder O².

The circulating-pump P consists of two cylinders p p', situated side by side and connected together by the passage m'. The suction-pipe enters the cylinder p at n, and the delivery-pipe is connected to the cylinder p' at n'. Upon the top of the circulating-pump 95 the fresh-water pump D is arranged. The piston on the plunger of this pump is utilized for drawing the fresh water from the condenser and forcing it through the filter Q, the annular space r round the pump-rod at the back 100 of the piston being used as an aerating-pump, the suction-valve r' being in communication with the atmosphere and the delivery-valve r² with the fresh-water-delivery pipe d². The brine-pump g' and condensed steam or boiler 105 feed-pump g⁴ are arranged one on each side of the steam-cylinder O², and are likewise operated by the cross-head O.

In order to cool and filter the water as it is pumped from the condenser, I pass the same 110 through a cooling-filter vessel Q, Figs. 1 and 2, into which the water to be filtered is introduced by the pipe d². A perforated plate q is placed over the tubes to distribute the flow of water. The upper part of the filter is divided 115 by a diaphragm and a transverse rib into two parts, into one of which fresh water is delivered from the condenser by the pump D. It then passes through a series of tubes c² to the lower part of the filter, and ascends again 120 through similar tubes c³ to the outlet S.

The water from the circulating-pump enters the pipe R², surrounds the whole of the said tubes, (thus further cooling the fresh water,) 125 and issues from the outlet R³, and passes thence to the condenser. The tubes c² c³ are filled with charcoal or other approved filtering medium to filter the water as it passes through the said tubes. The resulting product is thus cooled and filtered and excellent 130 to drink.

The action of the sea-water in the evaporator is as follows, viz.: As the water is heated in the tubes, it rises and displaces the cooler

water, which returns by the passages E, so that a constant circulation is kept up. As the steam is given off, it rushes through the slot j' into the annular space in the still-head 5 H and impinges upon the inclined baffle-plates K K', giving the steam a downward direction, so that any water that may be carried up by the steam will be thrown down to the bottom of the annular space, afterward 10 draining back into the evaporator through the space k between the bottom of the baffle-plate and the neck of the still-head, and also the water that may be left in the steam traveling round the annular space is thrown by 15 centrifugal force to the outer side, the steam rising to the top of the annular space, and escaping to the condenser by the pipe e, which projects inward at L. I may convert the evaporator into a condenser and work both 20 chambers as condensers.

I arrange the cocks e^2 , e^3 , s' , and s^2 and pipes t and s^3 on the live steam and circulating services, so that by opening the cocks E^3 , S' , and S^2 and closing cock E^2 , the circulating 25 water will pass through the evaporator, entering at t' and discharging through the cock s^2 into the main circulating-pipe R, live steam being admitted to the condenser B through the pipe f.

30 It is obvious that any suitable series of the apparatus may be combined together, the evaporated steam in the first evaporator being utilized for evaporation in the second apparatus instead of further live steam from 35 the boiler, and in such a case both chambers of the first and following apparatus may be utilized for evaporation, the final condensation only occurring in the last of the series, or the condensing-chamber of a single apparatus 40 may be used for secondary evaporation by the steam generated in the primary evaporator, and the ultimate and final condensation may be effected in or in a chamber connected to the main condenser of the engine.

45 Having now described my invention, what I claim is—

1. In an evaporating and condensing apparatus, the combination of an evaporator consisting of a closed vessel having transverse 50 internal diaphragms or divisions between which tubes are arranged, so that their ends

communicate to the upper and lower chambers formed by the said diaphragms, respectively, the chamber for the heating-steam being between the said diaphragms around the 55 tubes, a side passage or passages communicating between the said upper and lower chambers to effect the rapid circulation of liquid from the upper to the lower chamber, with a condenser for condensing the steam 60 from the said evaporator, a feed-regulating valve for maintaining a constant level of liquid in the evaporator, a steam-pump operating by one cylinder through a cross-head, a pump to circulate the surface-water in the 65 condenser, a fresh-water pump for withdrawing the fresh water from the condenser, an aerating-pump for aerating the fresh water, a brine-pump for withdrawing the brine or other matter from the evaporator, and a feed- 70 pump for returning the water condensed in the evaporator to the boiler, substantially as described.

2. In an evaporating and condensing apparatus, an evaporator having a still-head provided with a circular baffle-plate suspended from the upper part thereof in such a manner as to form an annular space therein, a slot being provided in the said baffle-plate extending nearly the whole of the depth, 75 forming communication between the interior and the annular space, also a small space being left between the bottom edge of the baffle-plate and still-head neck for draining liquid from the annular space, and two further baffle- 80 plates arranged one on each side of the said slot and lying around the annular space in an angular position from the top of the said space to nearly the bottom in a direction from said slot, an outlet for the steam being situated in the said annular space on the opposite side to the said slot, the interior orifice of this outlet being situated as near the central baffle-plate as possible, substantially as set forth.

In testimony whereof I have signed my 95 name to this specification in the presence of two subscribing witnesses.

HENRY FERGUSON.
